UNITED STATES PATENT OFFICE.

BENJAMIN STEIN, OF NEW YORK, N. Y.

DESIGN FOR A SUSPENDER-YOKE.

SPECIFICATION forming part of Design No. 35,687, dated February 4, 1902.

Application filed December 18, 1901. Serial No. 86,457. Term of patent 7 years.

To all whom it may concern:

Be it known that I, BENJAMIN STEIN, a citizen of the United States, and a resident of the city of New York, borough of Manhattan, in the county and State of New York, have invented and produced a new and original Design for a Suspender-Yoke, of which the following is a specification, reference being had to the accompanying drawings, forming a part thereof, in which—

Figure 1 is a side elevation of a suspender-yoke embodying the features of my design, and Fig. 2 is an edge view looking toward one side.

The leading features of the design consist of the two connected side wing-sections A and B, which curve upward and outward in opposite directions, and a downwardly-extending tab member C, forming a portion of the central section of the yoke and appearing continuous with the side wing-sections.

The minor features of the design consist in the convex end lines *a* and *b* of the side wing-sections and the convex end line *c* of the tab member, together with the concave marginal lines *d*, occurring where the outer edges of the tab member meet the lower edges of the wing-sections, and the concave line *e* at the upper central edge portion of the yoke.

Having thus described my invention, I claim as new and desire to secure by Letters Patent—

The design for a suspender-yoke herein shown and described.

In testimony whereof I have signed my name to this specification in the presence of two subscribing witnesses.

BENJAMIN STEIN.
